O. GEISLER

CLEANING DEVICE

Filed May 23, 1926

Patented Jan. 17, 1928.

1,656,479

UNITED STATES PATENT OFFICE.

OTTO GEISLER, OF CHICAGO, ILLINOIS.

CLEANING DEVICE.

Application filed May 28, 1926. Serial No. 112,346.

My invention relates to improvements in cleaning devices, and it consists in the combinations, constructions, and arrangements herein described and claimed.

An object of my invention is to provide a cleaning device which is adapted to clean fabrics in the form of window shades, curtains, drapes, rugs, carpets, maps, and numerous other articles.

10 A further object of my invention is to provide a device of the type described which has cleaning members constructed to efficiently clean the various types of fabric.

15 A further object of my invention is to provide a device of the type described which has automatically controlled means for stopping the rotation of the device at a predetermined point.

20 A further object of my invention is to provide a device of the type described which has novel means for automatically releasing the fabric that is being cleaned as the rotation of the device is stopped.

25 Other objects and advantages will appear in the following specification, and the novel features of the invention will be particularly pointed out in the appended claims.

30 My invention is illustrated in the accompanying drawings, forming part of this application, in which

Figure 1 is a front elevation of the device,

Figure 2 is an end elevation of the device,

Figure 3 is a fragmentary perspective view of the device,

35 Figure 4 is a section along the line 4-4 of Figure 1, and Figures 5, 6, 7 and 8 are fragmentary portions of the device.

40 In carrying out my invention, I provide supports 1 and 2 having adjustable bearings 3 therein which are adapted to receive a shaft 4. A drum 5 having a groove 6 disposed longitudinally therein is rigidly mounted upon the shaft 4 between the supports 1 and 2. The upper ends of the supports 1 and 2 are provided with bearings 7 and 8 in which stub shafts 9 and 10 are respectively disposed.

45 Brackets 11 having bearings 12 equally spaced around the outer edge of the brackets 50 are rigidly mounted upon the stub shafts 9 and 10. Shafts 13 which are provided with clutch ends adjacent the support 2 are rotatably disposed in the bearings 12. Cylinders 14, 15, 16, 17 and 18 are rigidly mounted upon the shafts 13 between the brackets 11.

The cylinder 14 is provided with spirally-disposed rubber sponges which are especially adapted to clean opaque shades, or the like. The cylinder 15 is provided with spirally-disposed squeegees. The cylinder 16 is provided with spirally-disposed relatively soft bristles. The cylinder 17 is provided with spirally-disposed bristles 19. The cylinder 18 is provided with spirally-disposed 60 65 felt strips.

In Figure 3, I have shown a fragmentary view of the cylinder 17 and the manner in which the bristles 19 are secured thereto. The cylinder 17 is provided with a plurality 70 of spiral grooves 20 into which U-shaped sections 21 are disposed. The bristles 19 are placed across the upper edges of the U-shaped sections 21, and small U-shaped sections 22 are placed upon the bristles and moved inwardly and secured in place by screws 23. The bristles 19 are now in the position shown in Figure 3. These sections are disposed in each of the grooves in the cylinder 17 from one end thereof to the other. The sponges, 80 squeegees, soft bristles, and felt strips are secured to their respective cylinders in the same manner in which the bristles 19 are secured to the cylinder 17.

The stub shaft 9 has a groove therein 85 which is adapted to receive a hand lever 24. The hand lever 24 is pivotally mounted upon the stub shaft 9 by means of a pin 25. The hand lever is provided with a fork-shaped end 26 having inwardly extending pins which are received in an annular groove of a stop pin 27. The free end of the stop pin 27 is receivable in openings 28 which are equally spaced in a circuitous path within the support 1, see Figure 2.

90 95 The drum and cylinder-actuating mechanism is composed of a drive shaft 29 which is provided with a rigidly mounted pulley 30 and a loosely mounted pulley 31. A clutch 32 is keyed to the inner end of the shaft 29 and is actuated by a hand lever 33. A beveled gear 34 is rigidly mounted upon the shaft 29 and is in mesh with a pinion 35. The pinion 35 is rigidly mounted upon a shaft 36 which carries a worm 37. A clutch 38 is disposed beneath the worm 37 and is adapted to engage and disengage the worm 37 with and from the shaft 36. A forked lever 39 is pivotally mounted at 40 upon the support 2 and is provided with a 100 roller 41. The forked end of the lever 39 straddles the clutch 38 and is provided with 105 110

inwardly extending pins 42 which are adapted to engage with the clutch. A leaf spring 43 is mounted upon the end of the drum 5 and is adapted to engage with the roller 41.

5 Spring-pressed fasteners 44 are disposed upon each end of the drum 5 adjacent the groove 6, and are adapted to rigidly hold a roller of a window curtain, or any suitable means for securing a fabric to the drum 5.

10 Lugs 45 are integral with the supports 1 and 2, and are adapted to engage with the spring-pressed fasteners 44 and automatically disengage them from the curtain roller, or other fabric-holding means.

15 A pipe 46 is disposed longitudinally above the drum 5 and is provided with a plurality of openings for permitting a cleansing fluid to be sprayed upon the fabric. A pipe 47 which is in communication with a water supply is provided with a plurality of openings and a valve 48 for turning on and shutting off the water supply. By turning on the valve 48, the water is forced through the openings and upon the fabric which is on 20 the roller 5.

From the foregoing description of the various parts of the device, the operation thereof may be readily understood. Let us assume that the operator wishes to clean an 30 opaque window shade. The shade is first unrolled and a roller placed in the groove 6 of the drum 5 and rigidly secured in place by the spring fasteners 44. The lever 24 is then forced inwardly, releasing the pin 27 and turned in either direction until the roller 14 is brought into vertical alignment with the shaft 4. The lever 24 may then be moved outwardly causing the pin 27 to be forced into the adjacent opening 28. The drum 5 40 may be moved toward or away from the roller 14 by means of the adjustable bearings 3.

The lever 33 is now actuated causing the clutch 32 to engage with the clutch end of the shaft 13 upon which the roller 14 is 45 mounted. When power is applied to the shaft 29, the roller 14 is rotated at a relatively fast speed. The lever 39 is actuated by forcing downwardly upon the end carrying the roller 41 thus causing the clutch 38 to engage the worm 37 with the shaft 36, and in this manner, the drum 5 is rotated at a relatively slow speed. As the drum 50 rotates the shade engages with the drum and is held in frictional engagement therewith.

When the drum 5 reaches the end of a revolution, the leaf spring 43 will engage with the roller 41 and cause the lever 39 to disengage the worm gear 37 from the shaft 36. In this manner, the power is cut off from the drum 5 and the engagement of the spring 43 with the roller 41 causes the drum to 60 stop its rotation. Approximately at the same time, the lugs 45 engage with the spring fasteners 44 and release them from 65

the curtain roller. The operator may readily remove the curtain from the drum if it is thoroughly cleansed. If the curtain is not thoroughly cleansed, the fasteners may be engaged with the roller again and the power applied to the drum and to the roller 14 for another revolution of the drum 5. At the end of each revolution, the power is released automatically from the drum 5, the same releasing means serving as a stop for the drum, and the fasteners 44 automatically released.

10 The shade may now be removed from the drum, turned over, and secured to the drum again for cleaning the other side of the shade. If it is desired, the lever 24 may be actuated to bring the roller 15 adjacent the drum. The roller 15 has spirally-disposed squeegees which may be used to press the wrinkles out of and substantially dry the shade.

15 The various rollers may be used for cleansing different qualities of fabric, as for instance, the bristle-containing rollers 16 and 17 are more especially adapted to clean rugs.

20 It will be observed that metallic plates such as printers' plates may be passed through between the drum 5 and any desired cylinder for cleaning the plates after they have been placed in a suitable solution. Furthermore, plates or strips formed of various materials such as celluloid may be passed through the device and be cleansed, if desired.

I claim:

1. A cleaning device comprising supports, a drum rotatably mounted upon said supports, means for securing a fabric to said drum, cleaning cylinders, means for moving one of said cylinders into engagement with said fabric, power means for rotating said cylinder at a relatively fast speed, and means cooperating with said power means for rotating said drum at a relatively slow speed.

2. A cleaning device comprising supports, a drum rotatably mounted upon said supports, means for securing a fabric to said drum, cleaning cylinders, means for moving one of said cylinders into engagement with said fabric, power means for rotating said cylinder at a relatively fast speed, means cooperating with said power means for rotating said drum at a relatively slow speed, and means for automatically releasing said drum from said power means.

3. A cleaning device comprising supports, a drum rotatably mounted upon said supports, means for securing a fabric to said drum, cleaning cylinders, means for moving one of said cylinders into engagement with said fabric, power means for rotating said cylinder at a relatively fast speed, means cooperating with said power means for rotating said drum at a relatively slow speed, and means for automatically releasing said drum from said power means, and for automatically

cally stopping the rotation of said drum at a predetermined point.

4. A cleaning device comprising supports, a drum rotatably mounted upon said supports, means for securing a fabric to said drum, cleaning cylinders, means for moving one of said cylinders into engagement with said fabric, power means for rotating said cylinder at a relatively fast speed, means cooperating with said power means for rotating said drum at a relatively slow speed, means for automatically releasing said drum from said power means, and for automatically stopping the rotation of said drum at a predetermined point, and means for releasing said cylinder from said power means.

5. A cleaning device comprising supports,

a drum rotatably mounted upon said supports, means for securing a fabric to said drum, cleaning cylinders, means for moving one of said cylinders into engagement with said fabric, power means for rotating said cylinder at a relatively fast speed, means cooperating with said power means for rotating said drum at a relatively slow speed, 20 means for automatically releasing said drum from said power means, and for automatically stopping the rotation of said drum at a predetermined point, means for releasing said cylinder from said power means, and 25 means for automatically releasing the fabric from said drum.

OTTO GEISLER.
